No. 1. Ezra Ripley (a proprietor of Johnson & Co.) Troy New York.
Letters Patent Design No 131. dated 30 July 1847

The schedule referred to, in these Letters Patent and making
part of the same.

To all whom these presents shall come Be it known that
I Ezra Ripley of Troy in the County of Rensselaer and State
of New York have invented or produced a new design for Stone
plates, and that the following is a full clear and exact descrip-
tion of the same, reference being had to the accompanying draw-
ings, making part of this specification, in which Fig. 1 is the
front of an air tight stone. In the centre of said front is shown
a funnel with an ornamental vase filled up with leaves, flowers
and buds marked A and on either side is shown a perpendic-
ular pilaster with ornamented work on the face of the same
as shown in B.

I claim as my invention and desire to secure by Letters
Patent the above design which is fully set forth in the drawings
accompanying this description
